UNITED STATES PATENT OFFICE.

GEORGE FRANÇOIS JAUBERT, OF PARIS, FRANCE.

MANUFACTURE OF HYDROGEN BY MEANS OF SILICON AND ITS ALLOYS.

1,366,185.

Specification of Letters Patent. Patented Jan. 18, 1921.

No Drawing.

Application filed July 29, 1920. Serial No. 399,928.

To all whom it may concern:

Be it known that I, GEORGE F. JAUBERT, a citizen of Swiss Republic, and residing in Paris, 155 Boulevard Malesherbes, France, 5 have invented certain new and useful Improvements in and Relating to the Manufacture of Hydrogen by Means of Silicon and Its Alloys, of which the following is a complete specification.

10 In the manufacture of hydrogen by means of silicon and alloys of silicon acting upon a concentrated solution of caustic alkali (French patent G. F. Jaubert, No. 430302 of 6th August 1910) explosions occur sometimes 15 when the silicon or its alloys contain impurities, more particularly phosphids due to the phosphates contained in the sand or in the coal which have served for the manufacture of silicon or its alloys, the said phosphids forming, when coming into contact with 20 water, phosphorated hydrogen, spontaneously inflammable.

Moreover, it seems an established fact that the quantity of the said phosphids increases 25 according as the percentage of the silicon alloy decreases. For instance alloys of ferro-silicon contain more phosphids when they are at 75% of silicon than when they are at 95%.

30 This seems to be due to the lower temperature of the electric furnace at which the first alloys are manufactured relatively to the second alloys.

On the other side, a unity of silicon costs 35 less with poor alloys than with rich alloys; a quantity of electric current equal to a kilowatt—24 hours gives 2 kilograms of ferro-silicon at 75% against one kilogram of ferro-silicon at 90 or 95%.

40 It is clear, therefore, that it would be very advantageous to be able to use poor alloys in full safety if it would be possible to avoid any dangers of explosions due to the formation 45 of the spontaneously inflammable phosphorated hydrogen which is formed owing to the decomposition of the above mentioned phosphids.

The present invention enables to obtain the above result and it consists in causing an 50 aqueous solution (distilled water, rain water, or ordinary water suitably purified if necessary) to react upon ferro-silicon in the state of powder; there is a slight escape of gases and the gases which are decomposed in the 55 first place are the phosphids.

The paste of ferro-silicon which is ob-

tained so to say in a "slaked" state may then without any danger, be introduced in a hydrogen generator, for instance in a generator of the type described in Patent No. 60 430302 of the 6th August 1910 since the phosphorated hydrogen which is spontaneously inflammable has been partly eliminated.

When using the said paste of ferro-silicon 65 some difficulties may be experienced, but they can be overcome in the following manner:

In spite of the considerable difference of density existing between water and ferro-silicon at 75 or 95%, it is possible to make 70 mixtures of equal volumes (100 liters of ferro-silicon in the state of powder for instance and 100 liters of water) and to maintain the said mixture in a homogeneous suspension, simply by stirring. 75

During the stirring, the greatest part of the harmful gases is eliminated.

The semi-pasty liquid is entirely homogeneous and may then be distributed by means of a pump for instance (diaphragm or 80 plunger pump) either directly to the hydrogen generator, or to an intermediary distributing member with a variable delivery such as a conveying screw or any other apparatus.

The pump is generally sufficient and gives 85 good results.

The paste of ferro-silicon is then injected into the hydrogen generator, either at the upper part whence it falls into the alkaline liquid in motion, or on the contrary under 90 the alkaline liquid itself.

The described process enables consequently to obtain not only a purer gas, since a large part of the gaseous phosphorated derivates is eliminated beforehand, but moreover prevents any accident to be caused by a spontaneous inflammation, as those which have often occurred.

The present process does away also with another cause of accident, that is with a sudden flow of the whole mass of silicon powder from the distributing device of the apparatus of the type used at present and described in Patent No. 430302, into the generator. 100

The said accident seems to happen with those qualities of silicon which give an important percentage of very fine powder when pulverized. By putting into contact with an alkaline liquid, a mixture of silicon and 110 water instead of dry powder of silicon a much more rapid reaction is obtained: it

commences almost immediately and the output per hour of the apparatus is appreciably increased.

What I claim is.

5 1. The method herein described of manufacturing hydrogen, consisting in adding water to powdered ferro-silicon to decompose the phosphids contained in the ferro-silicon and form a pasty mass, and then adding the 10 pasty mass to a solution of caustic alkali in a hydrogen generator.

2. The method of manufacturing hydrogen, consisting in mixing pure water with powdered ferro-silicon to decompose the 15 phosphids contained in the ferro-silicon and

to form a pasty mass, and then reacting on said mass with caustic alkali.

3. The method herein described of manufacturing hydrogen consisting in mixing equal volumes of ferro-silicon in the state of 20 powder and water, in stirring the said mixture in order to eliminate phosphids, and in injecting the semi-pasty liquid of ferro-silicon obtained, into a hydrogen generator containing caustic alkali, either above or below the alkaline liquid. 25

In testimony I have hereunto set my hand at Paris (France) this ninth day of July 1920.

GEORGE FRANÇOIS JAUBERT.
